United States Patent Office

Des. 196,893
Patented Nov. 12, 1963

196,893

UNITARY BASE FOR A SPHYGMOMANOMETER OR THE LIKE

William A. Baum, New York, N.Y., assignor to W. A. Baum Co., Inc., Copiague, Long Island, N.Y., a corporation of New York

Filed July 31, 1962, Ser. No. 71,120

Term of patent 7 years
(Cl. D83—12)

FIG. 1 is a view in perspective of the unitary base for a sphygmomanometer or the like support showing my new design;

FIG. 2 is a top view of my design; and

FIGS. 3, 4 and 5 are elevational views thereof taken from the front, side and rear, respectively.

I claim:

The ornamental design for a unitary base for a sphygmomanometer or the like, substantially as shown.
